(57) CLAIM

The ornamental design for a footwear footbed, as shown and described.

DESCRIPTION

FIG. 1 is a lateral perspective view of a footwear footbed showing my new design;

FIG. 2 is a right side elevational view thereof;

FIG. 3 is a left side elevational view thereof;

FIG. 4 is a top plan view thereof;

FIG. 5 is a front elevational view thereof; and,

FIG. 6 is a rear elevational view thereof.

The broken lines in FIGS. 1-6 represent portions of the footwear that form no part of the claimed design. The broken line which defines the bounds of the claimed design forms no part thereof.
